UNITED STATES PATENT OFFICE.

HENRY L. LITCHFIELD AND EDGAR C. LITCHFIELD, OF WEBSTER CITY,
IOWA.

DESIGN FOR AN END-GATE EXTENSION.

SPECIFICATION forming part of Design No. 33,688, dated December 11, 1900.

Application filed November 10, 1900. Serial No. 36,139. Term of patent 14 years.

To all whom it may concern:

Be it known that we, HENRY L. LITCHFIELD and EDGAR C. LITCHFIELD, citizens of the United States, residing at Webster City, in the county of Hamilton and State of Iowa, have produced a new and original Design for an End-Gate Extension, of which the following is a specification.

This invention relates to a design for an end-gate extension, and the essential feature resides in the design disclosed by the accompanying drawings, wherein—

Figure 1 is a perspective view of the end-gate, showing the design and looking toward the bottom thereof. Fig. 2 is a sectional side elevation of the same.

The numeral 1 designates a bottom member having one side edge formed with a curved bevel 2, and against the under side of the said bottom member is a rectangular strip 3, projecting beyond the edge thereof opposite that having the curved bevel. The terminals of the strip are extended beyond the planes

of the ends of the bottom member, and inward from the said terminals are transverse 25 projections 4. From the bottom member rise opposite sides 5, each having an angular extension 6 and the rear edges 7 inclined regularly from the lower portions of the same upwardly toward the top of the sides and gradually reduce the width of said sides toward their upper extremities. The sides have outer angular projections 8 and rounded projections 9 above the latter.

Having thus described the invention, what 35 is claimed as new is—

The design for an end-gate extension, herein shown and described.

In testimony that we claim the foregoing as our own we have hereto affixed our signatures 40 in the presence of two witnesses.

HENRY L. LITCHFIELD.
EDGAR C. LITCHFIELD.
